UNITED STATES PATENT OFFICE.

ARTHUR J. KELLY, OF KANSAS CITY, MISSOURI.

INLET AND TRAP FOR SEWERS.

SPECIFICATION forming part of Letters Patent No. 242,329, dated May 31, 1881.

Application filed February 26, 1881. (No model.)

To all whom it may concern:

Be it known that I, ARTHUR J. KELLY, a citizen of the United States, resident at Kansas City, in the county of Jackson and State 5 of Missouri, have invented certain new and useful Improvements in Inlets and Traps for Sewers; and I do hereby declare the following to be a full, clear, and exact description of the invention, such as will enable others skilled 10 in the art to which it appertains to make and use the same, reference being had to the accompanying drawings, and to letters or figures of reference marked thereon, which form a part of this specification, in which—

15 Figure 1 is a representation of a side view of my invention, and Fig. 2 is a vertical section thereof.

This invention relates to improvements in sewer traps and inlets.

20 The invention consists in the construction hereinafter described, and particularly pointed out in the claim.

In the drawings hereto annexed, A represents the roadway having the ordinary pitch 25 to the gutter B, as shown.

C is the sewer-cap, and D is the cover to the man-hole.

E is the opening for the water to drain through. At the bottom is the plate F. Running 30 from the plate F to cap C is the grating G, composed of bars. This plate F has the curved form shown, and the grating takes this turn. The bars G run backward in a slant and have the pitch shown, which raises the 35 rubbish to the top and better enables the water to pass into the receiver.

H is the receiver for the water, made of brick-work, and I is the outlet-pipe connected with the sewer.

40 At K, the top of the opening L of the outlet

I, is secured a plate, M, having lugs m, with perforations a a, said lugs extending out into the receiver or trap, as shown. Hung upon these lugs by eyes n n is a cover or apron, N, the edge b of which projects below the lower 45 face, c, of the outlet I.

d designates wedges, preferably of wood, for securing the plate or apron N in place upon the lugs m.

B' B' are inclined flanged metal pieces at 50 the ends of plate F for the curb to abut against.

By reason of the fact that the plate or apron N, when not inverted, extends below the lower face, c, of the outlet I, a water-seal is formed in the receiver H, which prevents the gases in 55 the sewer from escaping into the receiver and thence to the air. In cases, however, where the sewer trap or inlet is used in localities where the road-bed is not macadamized or paved, the plate N should be inverted by removing the wedges and turning the plate up against the plate F and again replacing the wedges d. This is necessary in order to permit the trash to pass off through the outlet I. In such instances the escape of sewer-gas can- 60 not be prevented.

What I claim is—

In an inlet or trap for sewers, the combination, with the plate M, having the inwardly-projecting perforated lugs m a, of the removable 70 plate or apron N, adapted to extend below the lower face of the outlet I, and the wedges d, for securing the plate N to place, substantially as and for the purposes set forth.

In testimony whereof I affix my signature 75 in presence of two witnesses.

ARTHUR J. KELLY.
